INVENTOR.
WILLIAM A. BRUNO

BY

William Bruno

UNITED STATES PATENT OFFICE

2,359,351

CONNECTING DEVICE

William A. Bruno, New Hyde Park, N. Y., assignor
to the firm Bruno Patents Inc., Long Island
City, N. Y.

Application October 14, 1942, Serial No. 461,959

3 Claims. (Cl. 174—21)

This invention relates to an electrical connecting device adapted to provide electrical connection between a stationary structure and a second structure which is capable of rotary movement relative to said stationary structure, said connecting device being also adapted to form a gaseous connection with said second structure upon rotatably coupling the connecting device with a stationary gas supply source. The invention has particular relation to a connecting device of this type, which is adapted to be used for providing electrical and gaseous connection between a rotary turret and stationary parts in air-planes, tanks, armoured cars and the like.

The main object of my present invention is to provide an improved connecting device of the above mentioned type, which carries electrical connecting means, and is adapted to provide a gaseous connection upon being rotatably connected with a gas supply source.

It is another object of my invention to provide a connecting device which comprises a stationary unit carrying electrical contact elements and a tubular unit which also carries electric contact elements and is rotatably housed by said stationary unit and adapted to form a gaseous connecting means.

A further object of my invention is to provide a connecting device consisting of relatively few parts, which can be easily assembled and taken apart.

Other objects and advantages will appear to those skilled in the art from the following specification and the appended drawings which show, by way of example, a preferred embodiment of my invention, and in which

Figure 1 is a longitudinal sectional view of a connecting device according to my invention.

Figure 2 is an end view looking at the right end and taken along the line 2—2 of Figure 1.

Figure 3 is another end view looking at the left end of Fig. 1 in the drawings;

Figure 4 is a sectional view taken along the line 4—4 of Fig. 1, and

Figure 5 is an outside elevational view of the device.

Referring now to the drawings, a panel 1, to which the connector is fastened, is shown in Fig. 1. 2 is a flanged stationary tube which consists, for example, of phosphor-bronze, carries a barrel 3, and rotatably houses the gas supply pipe 12. A protecting element, which may consist of felt, is inserted, as shown at 43, to prevent dust and other impurities from entering the device. The internal surface of the right end of

tube 12 is provided with a pipe thread 12' and the left end of a pipe 12'' is screwed in the right end of pipe 12. The other end of pipe 12'' is rotatably connected with a stationary gas supply source 61. This device 61, which does not form a part of my present invention, is diagrammatically indicated in the drawings. A contact ring assembly is secured to the outer cylindrical surface of tube 2. This contact ring assembly contains four contact rings 5, which are insulated from each other and from the tube 2 by insulating parts 6. The contact ring assembly is held assembled by discs 42 and 42'. Each of the contact rings 5 has an electrically insulated duct

10 bolt 9, and is connected with a soldering lug 10. The incoming four wire cable (not shown in the drawings) is connected to these soldering lugs 10.

Rigidly secured by screws 65 to the rotatable gas supply tube 12 is a bell-shaped metallic body

20 15, which carries four properly insulated contact elements 16. Each of these contact elements 16 is electrically connected to a contact spring 17, which is also properly insulated from body 15. These contact springs are situated in four different planes in such a manner that each contact spring glides on and forms electrical parallel contacts with one of the contact rings 5 at two spaced points. Each of these springs is secured to the body 15 by a pair of properly 25 insulated rivets 18. The left end of contact elements 16 is provided with a soldering lug 21, to which the outgoing leads (not shown) are soldered.

The left end of the rotatable gas supply tube 35 12 is provided with an exterior pipe thread 62 and connected with threaded tube elements 63. A cover 71 provided with a clamp 71' and adapted to receive the incoming cable, is secured to barrel 3, and a similar cover 72 provided with clamp 72' and having an opening for the outgoing cable is secured to body 15 by means of 40 screws 47. A notched spring element 73 and a washer 73' is inserted between barrel 3 and a shoulder of tube 12.

45 As will be understood from the above description and the drawings, the connecting device according to this invention can be easily assembled and taken apart. Owing to its simple construction, it represents a durable and safe electrical and gaseous connecting means which is not affected by sudden changes of atmospheric conditions and can also be used for supplying a gas under superatmospheric pressure.

50 While I have shown and described certain preferred embodiments of the invention, it is to

be understood that the invention is not limited to the embodiments and details shown but may be otherwise variously embodied and practiced within the scope of the appended claims.

I claim:

1. A system for connecting stationary electrical and gaseous sources with a rotatable structure, said system comprising a stationary cylindrical tube carrying on its outer cylindrical surface a concentrically arranged stationary electrical contact ring assembly, the inner cylindrical surface of said stationary tube forming a bearing for an intermediate portion of a rotatable gas supply tube, both ends of said rotatable gas supply tube projecting from said stationary tube, the outer surface of one projecting end of said rotatable gas supply tube carrying a bell-shaped cylindrical body housing electric connecting means comprising contact springs adapted to make rotatable electrical contact with the contact rings of said contact ring assembly, and the other projecting end of the rotatable gas supply tube being adapted to be rotatably connected with a stationary gas supply source.

2. A system for connecting stationary electrical and gaseous sources with a rotatable structure, said system comprising a stationary cylindrical tube carrying on its outer cylindrical surface a concentrically arranged electrical contact ring assembly, the inner cylindrical surface of said stationary tube forming a bearing for an intermediate portion of a rotatable gas supply tube, both ends of said rotatable gas supply tube projecting from said stationary tube, the outer surface of one projecting end of said rotatable

gas supply tube carrying a bell-shaped cylindrical body fastened to said one projecting end of said rotatable tube, said bell-shaped body housing electric connecting means comprising

5 contact springs adapted to make rotatable electrical parallel contact with the stationary contact rings of the contact ring assembly at two spaced points, and the other projecting end of the rotatable tube being adapted to be rotatably connected with a stationary gas supply source.

10 3. In a device for connecting stationary electrical and gaseous sources with a rotatable structure, a stationary cylindrical tube carrying on its outer cylindrical surface a stationary 15 contact ring assembly, the inner cylindrical surface of said stationary tube forming a bearing for an intermediate portion of a rotatable gas supply tube, both ends of said rotatable gas supply tube projecting from said stationary tube, the outer surface of said one projecting end of said rotatable tube carrying a bell-shaped cylindrical body housing electric connecting means comprising contact springs adapted to make rotatable electrical contact with the contact rings 20 of the contact ring assembly, the other projecting end of the rotatable tube being adapted to be rotatably connected with a stationary gas supply source, a barrel carried by one end of said stationary tube, said barrel being connected with a first cover provided with a clamp and being 25 adapted to receive the incoming electric cables, a second cover carried by said body, said cover being provided with a clamp and adapted to receive outgoing electrical cables.
